FIG.1

FIG.2

FIG. 1 is an isometric view from above of a core for roof insulation ventilators, the view showing my new design; and

FIG. 2 is an isometric view from below of the core shown in FIG. 1.

The core is embedded in built-up roofing material so that the bottom of the core opens into the area below the layers of insulation while the top of the core communicates with the interior of the ventilator structure above the roof.

I claim:

The ornamental design for a core for roof insulation ventilators, as shown and described.
